UNITED STATES PATENT OFFICE.

PETER G. NEISENDORFER, OF BALTIMORE, MARYLAND.

COMBINED BUNG-BUSH AND STAMP-PROTECTOR.

SPECIFICATION forming part of Letters Patent No. 286,474, dated October 9, 1883.

Application filed February 19, 1883. (No model.)

To all whom it may concern:

Be it known that I, PETER GEORGE NEISENDORFER, of Baltimore, in the county of Baltimore and State of Maryland, have invented certain new and useful Improvements in Combined Bung-Bush and Stamp-Protector; and I do hereby declare that the following is a full, clear, and exact description thereof, reference being had to the accompanying drawings, and to the letters of reference marked thereon, which form part of this specification, in which—

Figure 1 is a vertical section taken centrally through the improved bung-bushing and its hinged covering-ring, showing the spring-bolt applied to said ring, and in section also showing a revenue-stamp applied to said parts with a bung inserted. Fig. 2 is a top view of the device, showing the hinged covering-ring thrown back.

This invention relates to bushings for beer barrels, and also to a combination with such bushings of seats and coverings for the seats, whereby revenue-stamps are protected on the barrels after they are canceled; and the nature of my invention consists in a hinged capping-ring, a cup-shaped cap for a bushing, and a spring-holder for the capping-ring; also, of spurs on the flanged capping portion of the bushing, all of which will be fully understood from the following description when taken in connection with the annexed drawings.

A designates a tube which is internally beveled so that it flares outwardly with respect to the barrel when applied thereto, and which has a male screw cut on it. This tube is made of metal, and it is cast with a flange, *a*, at its upper end, which flange has a rim, *b'*, partly surrounding it. At the terminus of the rim *b'* are cast eyes *b b*, adapted to receive through them a pintle, *b²*, which forms a hinge and unites a ring-cap, *B*, to the bushing. Inside of the flange of the rim *b'* of the bushing, and cast integral therewith, are two lugs, *l l*, and at right angles thereto, on one side, a bow spring, *S*, is applied, opposite which a recess, *g*, is made into the flange, and in a direct line with this recess a perforated lip, *h*, is raised on the flange.

At the point indicated by the letter *g'* a tubular enlargement is made on the capping-ring *B*, and in which a coiled spring, *s*, is applied, the object of which is to act on a bolt, *b⁴*, which has a beveled nose adapted to enter the perforated lip *h* on the rim of the bushing.

Now, when the ring is shut it lies flush within the rim *b'*, and is locked snugly therein by the spring-bolt *b⁴*, above referred to.

The main object which I have in view is to prevent any portion of a revenue-stamp, when applied to a beer-barrel, from being so obliterated that it cannot be identified after the bung has been forced through it.

I am aware that a metal strap has been crossed over a revenue-stamp after it has been applied over the bung of a beer-barrel, and that said strip has been tacked to the barrel. This I do not claim as my invention.

It will be seen that I have a recess formed in the exterior part of a beer-barrel bushing, 70 adapted to receive a paper, on which may be a revenue-stamp or any other imprint which it is desired to cancel, and that the cancellation can be effected not only by the closing of the hinged ring-cap, but also by the introduction of the bung into the barrel through said ring-cap; and it will also be seen that while said advantages are obtained, I also have the further advantage of preventing the canceled parts of the United States revenue-stamp 80 from being washed or rubbed from the parts surrounding the outside of the bung of the barrel.

Having thus fully described my invention, what I claim as new, and desire to secure by 85 Letters Patent, is—

1. A bung-bush consisting of a tubular external screw-threaded portion having a tapered bore and a flange which is cup-shaped, a cap having a hole through its center, a spring-actuated bolt for locking the cap down in place in said cup, and a spring for throwing up the cap when released from its bolt-fastening, all constructed and adapted to operate substantially in the manner and for the purposes described. 95

2. The combination of a screw-threaded bush, a cupped seat thereon, a ring-cover hinged thereto, a spring for lifting said cover, and a spring locking-bolt therefor, all constructed and adapted to operate substantially in the manner and for the purposes described. 100

In testimony that I claim the foregoing as my own I affix my signature in presence of two witnesses.

P. G. NEISENDORFER.
